UNITED STATES PATENT OFFICE.

ADOLF WEISS, OF BROOKLYN, NEW YORK, ASSIGNOR TO ROBERT J. MASBACH, OF NEW YORK, N. Y.

ROASTING APPARATUS.

1,212,859.

Specification of Letters Patent.

Patented Jan. 16, 1917.

Application filed July 12, 1916. Serial No. 108,787.

To all whom it may concern:

Be it known that I, ADOLF WEISS, a citizen of the United States, and a resident of the borough of Brooklyn, county of Kings, 5 city and State of New York, have invented certain new and useful Improvements in Roasting Apparatus, of which the following is a specification.

My improvements relate to apparatus 10 used for roasting coffee, peanuts, grains or other natural products, and are designed to render the use and manipulation of such apparatus more safe, convenient and expeditious than heretofore, a distinctive feature 15 of the invention being the provision of the roasting drum with hinged doors held in closed relation normally by latches which may be tripped as desired to open the doors and discharge the contents of the heated 20 drum without removing or touching the latter manually, as hereinafter more fully set forth.

Figure 1, is a front elevation of my improved roasting apparatus; Fig. 2, a top view thereof; Fig. 3, a transverse vertical section taken upon plane of line 3—3, Fig. 4; Fig. 4, a central vertical longitudinal section of the casing, showing the other parts in elevation; Fig. 5, is a detail isometrical 30 view of one of the latches; Fig. 6, is a view of the drum or cylinder, showing the doors thereof; Fig. 7, is a sectional view of the drum doors on a larger scale; Fig. 8, is a sectional elevation showing a modification 35 in the form of tripping device.

C, represents the rectangular trunk or body of the casing supported upon legs or standards c, c, and provided with a hinged 40 semi-cylindrical cover C', for which rearwardly projecting rests c', c', are provided at the back of the trunk C, to support the cover C', when raised. Open bearings c², c², are formed on the side members of the 45 casing C, on which the journals d, d, of the cylindrical roasting drum D, rest, one of said journals being provided with a crank d', or equivalent means whereby the said cylindrical drum D, may be rotated on its 50 axis.

The roasting drum D, is formed with one or more doors d², extending longitudinally practically the whole length of the cylinder. Preferably two such doors are provided, as 55 shown more particularly in Figs. 6, and 7,

of the drawings, one overlapping the other so that the overlapping one will hold the other in place when closed and latched,—said overlapping door being formed with protuberant studs or shoulders d³, d³, at 60 either extremity for engagement with the latches a, a, mounted upon the ends of the roasting drum D.

Obviously various forms of latch and trip mechanism may be employed for the purpose 65 of securing and releasing the doors d², d², and I do not limit myself in this respect to the identical form, construction or arrangement of parts herein shown since other mechanical expedients and equivalents may be 70 substituted with like result and without departing from the spirit and intent of my invention. As shown however, by way of illustrating the principle involved, latches a, a, are pivotally attached, one to each head or 75 end of the drum D, as at d⁴, the outer end of the latch a, being formed with notch or shoulder a', adapted to engage with the pro- 80 tuberant stud or shoulder d³, on the corre- 85 sponding end of the door d², when the latter is closed and being held in engagement therewith by a retractile spring a², attached at one end to the latch a, and at the other to the end of the drum D, it being under- 90 stood that these latches, etc., are duplicated 95 at each end of the latter. The swing or play of each latch a, is limited and controlled by a strap d⁵, upon each end of the drum as indicated particularly in Fig. 3. Obviously 90 when the door is, or doors are closed and the latches a, are in engagement with the protuberances d³, the springs a², will tend 100 constantly to hold the parts in locked relationship so that the roasting drum D, may be rotated freely and continuously without danger of spilling the contents previously introduced through the open doors facing upward and with the cover C', thrown back for the purpose.

When it is desired to release the contents of the drum D, the latches a, are thrust back against the resistance of the springs a², by trips t, which are caused to protrude into the paths of the outer ends of the latches a, 105 as they rotate with the drum.

In Figs. 3, to 6, inclusive the free ends of the latches a, are shown as formed with lateral projections a³, to insure contact with trip arms t, projecting upward vertically 110

from a trip-frame lever t' , pivotally attached to brackets c^3 , c^3 , on the trunk casing C, the inner cross bar t^2 , of said trip-frame lever t' , resting normally upon a bracket 5 or support c^4 , on the inner side of said trunk casing C, see particularly Figs. 3 and 4. Thus when the front cross member t^3 , of the trip-frame lever t' , is depressed, the trip arms t , will be projected into the path of 10 the lateral projections a^3 , of the latches a , which latter will consequently contact with the trips t , as the drum rotates, thus automatically releasing the door or doors d^2 , against the resistance of the springs a^2 , so 15 that the contents of the roaster drum D, will be discharged by gravity into a receptacle R, placed immediately below for the purpose, it being noted of course that the trip mechanism is so positioned as to release the door or doors when the latter are 20 in lowest position underneath the drum D.

In the modification shown in Fig. 8, the trips t , t , consist of spring actuated bolts which may be released to protrude laterally 25 into the paths of the free ends of the latches a , a . These trip-bolts t , are supported in fixed sleeves t^4 , formed with longitudinal slots t^5 , with lateral offsets for the accommodation of studs t^6 , on the trip-bolts t , 30 whereby the latter may be held back against the resistance of springs t^7 , until the trips t , are set to intercept and throw open the latches a , a , substantially as hereinbefore set forth in connection with the tripping mechanism shown in the other prior figures 35 of the drawings.

C^8 , is the front door of the trunk body C, hinged to the latter and held in place by button fastenings c^8 , c^8 , or other mechanical 40 expedients.

c^5 , c^5 , are the handles of the trunk casing C.

c^6 , is the usual vent hole in the cover C' , closed or controlled by the usual slide or 45 damper c^7 , see particularly Fig. 2. The receptacle for the roasted products is also provided with handles r , r , and may be withdrawn from underneath the drum D, and trunk casing C, at either end of the latter 50 between the legs c , c .

The roasting drum D, is heated externally by any suitable means positioned within the trunk casing C, as by means of the twin gas burners g , g , shown in the drawings, connected with a common gas head or supply conduit g' , which is connected in turn with a gas supply pipe, etc., in a manner well known in the art.

It will be seen that by my construction 60 and arrangement of parts the contents of roasting drum D, may be quickly and conveniently discharged into the receptacle R,

by simply setting the trips t , t , to intercept and retract the latches a , a , and release the 65 protuberances or shoulders d^3 , d^3 , on the door d^2 , as indicated in dotted lines in Fig. 3. This setting of the trip mechanism may be accomplished externally, and without touching any heated part of the apparatus, 70 whereas heretofore it has been customary if not absolutely necessary to unship and lift the drum out of its casing and to shake out the roasted products prior to recharging.

By providing for the opening of the door 75 when the latter is in the lowest position under the drum I insure the automatic discharge of all the contents of the drum; and when the cover C' , is raised and the drum turned with the doors upward the 80 drum may obviously be quickly and conveniently charged with fresh material for roasting.

What I claim as my invention and desire 85 to secure by Letters Patent is,

1. In roasting apparatus of the character designated the combination of a rotatable roasting drum formed with a hinged door, latch mechanism on the drum for holding said door closed, and trip mechanism supported independent of said drum and adapted to be set to trip the said latch mechanism on the drum, for the purpose described.

2. In roasting apparatus of the character designated, the combination of a rotatable 95 roasting drum formed with two hinged doors one overlapping the other, latch mechanism on the drum for holding said doors closed, and trip mechanism supported independently of said drum and adapted 100 to be set to trip the said latch mechanism on the drum.

3. In roasting apparatus of the character designated, the combination of a rotatable roasting drum formed with a hinged door, 105 spring latch mechanism on the drum for holding said door closed, and trip mechanism supported independent of said drum and adapted to be set to trip the said spring latch mechanism on the drum, for the purpose described.

4. In roasting apparatus of the character designated, the combination of a rotatable roasting drum formed with two hinged doors one overlapping the other, spring 115 latch mechanism on the drum for holding said doors closed, and trip mechanism supported independently of said drum and adapted to be set to trip the said spring latch mechanism on the drum.

ADOLF WEISS.
